UNITED STATES PATENT OFFICE.

SAMUEL S. MATTHES, OF MANSFIELD, OHIO, ASSIGNOR TO THE OHIO BRASS COMPANY,
OF MANSFIELD, OHIO, A CORPORATION OF NEW JERSEY.

CONDUCTOR SUPPORT.

Application filed March 25, 1922. Serial No. 546,698.

To all whom it may concern:

Be it known that I, SAMUEL S. MATTHES, a citizen of the United States of America, residing at Mansfield, in the county of Rich-
5 land and State of Ohio, have invented cer-
tain new and useful Improvements in Con-
ductor Supports, of which the following is
a specification.

My invention relates to improvements in
10 conductor supports and resides more partic-
ularly in what are known as renewable tips
for conductor supports.

The object of my invention is to produce
a device which can be used in combination
15 with such conductor supports as are known
in the trade as trolley frogs or switches, sec-
tional insulators, trolley wire crossings, etc.,
and which in combination with such devices
will force and maintain the trolley conduc-
20 tor in place and which is capable of being
made of brass or bronze where the other
parts of the support may be made of malle-
able iron or other ferric metal, thereby pro-
ducing a construction very much cheaper
25 than if the whole device were made of bronze
or other expensive material. It is possible
to carry out this combination as the extreme
tips can be made of bronze whereby any
arcing that may occur when a trolley wheel
30 passes from the device on to the trolley wire
will be a minimum which would not be the
case if the whole device, including the tip,
were made of malleable iron.

My invention resides in the construction,
35 combination and relation of the various parts
herein fully set forth and described.

In the drawing accompanying the specifi-
cation:—

Fig. 1 is a side view of my invention in
40 combination with the end of an overhead
frog, sectional insulator or other device used
in supporting a trolley wire.

Fig. 2 is a top view of Fig. 1.

Fig. 3 is a view in section on the line 3—3
45 of Fig. 1.

Fig. 4 is a view in section on the line 4—4
of Fig. 1.

In my preferred construction the member
1 is the end of a trolley frog, sectional insu-
50 lator or other trolley wire support.

The member 2 is a removable end which
forces the trolley conductor 3 into position
and maintains it in that position. The mem-
ber 1 at its extreme end is formed with a ta-
55 pered opening 4 having its greater dimen-

sion at the extreme exterior and the upper
edge of the member 1 is formed with a slot 5
which opens into the recess 4. The opening
5 permits the trolley wire 3 to be entered
into the recess 4 and if it is found advisable
60 the walls 6 may be cast as indicated by the
dotted lines 7 in Fig. 3 thereby giving a
greater width to the slot 5 and the walls can
then be forced inwardly after the wire has
been entered within the recess 4.

The end of the member 2 is formed with
the tapered portion 8 so shaped as to con-
form to the opening 4 so far as its upper
and lower edges are concerned, after the
trolley wire is in position. The opposite
70 end of the member from the tapered portion
8 is formed with a channel 9 having depend-
ing lips 10—10 adapted to receive the trolley
wire 3 and the lips to be formed about the
trolley wire after the member 2 is in position
75 with respect to the member 1.

In installing my invention the trolley wire
is first passed into the slot 5 into the recess
4. The tapered end 8 of the member 2 is
then inserted into the recess 4 and forced
80 back into the recess 4 by means of hammer
blows applied to the hammer lug 11. After
the member 2 has been forced into position
and the trolley wire down against the lower
inner edge of the recess 4 one or both of the
85 bendable lugs 12 are bent over to engage the
member 2 to maintain the member 2 in pos-
ition. The lips 10 are then bent about the
trolley wire as shown in Fig. 4 thereby com-
pleting the installation upon the trolley
90 wire.

As my invention I claim:—

1. A support for trolley conductors com-
prising a body member provided with a slot
for the conductor, the slot terminating in an
enlarged opening having tapered walls, a
95 detachable member having a tapered portion
at one end to enter the enlarged opening and
engage its tapered walls and the trolley con-
ductor to force into and retain in place the
conducto, means on the detachable member
100 exterior of the body member to receive the
conductor and means on the body member to
engage the detachable member to maintain
the two members in position.

2. A support for trolley conductors com-
prising a body member provided with a slot
for the conductor, the slot terminating in an
enlarged opening having tapered walls, a
105 detachable member having a tapered portion
110

at one end to enter the enlarged opening and engage its tapered walls and the trolley conductor to force into and retain in place the conductor and means on the body member to engage the detachable member to maintain the two members in position.

3. A support for a trolley conductor comprising a body member to receive a conductor, a longitudinally slidable member 10 having a wedging engagement with the body member and the conductor and having a portion to engage and grip the conductor exterior of the body member and means on one member to engage means on the other member to prevent longitudinal movement of the members in a direction away from each other.

4. A support for a trolley conductor comprising a body member provided with means 20 to receive the conductor, a portion of said means consisting of an enlarged recess having tapered walls to receive a detachable member to engage the conductor to force it into and maintain it in place, a detachable member provided with a tapered end to enter the tapered recess, means on the detachable member to receive the impact of a blow applied to the detachable member to force the detachable member into place and means

on the body member to engage the detachable member to retain them together.

5. An article of manufacture comprising a body member provided with means to receive a conductor, the means terminating in an enlarged tapered recess open at both ends 35 and having its larger opening away from the body member, a detachable member adapted to enter the recess and be forced into engagement with the walls of the recess and the conductor to move the conductor into place 40 and retain it therein and means on one of the members to engage the other member for retaining the members against separation.

6. A support for a trolley conductor comprising a body member to receive the conductor, a longitudinally slidable member having a wedging engagement with the body member and the conductor to force and maintain the conductor in place and having means external to the body member to receive and engage the conductor and means on one member to engage means on the other member to prevent the relative movement of the members in a direction away from each other.

In testimony whereof I affix my signature.

SAMUEL S. MATTHES.
